UNITED STATES PATENT OFFICE.

JOHN CLITHEROE, OF ATTLEBORO FALLS, MASSACHUSETTS, ASSIGNOR TO INTERNATIONAL BRAID COMPANY, OF PROVIDENCE, RHODE ISLAND, A CORPORATION OF MASSACHUSETTS.

TUBULAR-WICK BURNER.

Application filed July 12, 1922. Serial No. 574,502.

To all whom it may concern:

Be it known that I, JOHN CLITHEROE, a citizen of the United States, residing at Attleboro Falls, in the county of Bristol and State of Massachusetts, have invented certain new and useful Improvements in Tubular-Wick Burners, of which the following is a specification.

This invention relates to improvements in tubular-wick oil-burners and more particularly to the tubular sleeve member which embraces and carries the tubular wick; and the object of this invention is to provide simple and effective means in a burner of this character for attaching the wick to its carrier whereby a movement of the carrier by rotating the feed gears, will serve to positively move the wick a corresponding distance.

20 A further object of the invention is to provide a tubular carrier with a pair of integral prongs cut from the stock and turned inwardly to extend through the wick fabric and be clinched on the inner side thereof.

25 With these and other objects in view, the invention consists of certain novel features of construction, as will be more fully described, and particularly pointed out in the appended claims.

30 In the accompanying drawings:

Figure 1 is a sectional side elevation showing a portion of the oil fount with my improved wick-carrier operatively mounted therein and partly broken away to better illustrate its structure.

35 Figure 2 is a sectional end view showing the adjusting gear in mesh with the openings in the carrier tube, also as being sectioned through the wick-engaging prongs.

40 Figure 3 is an enlarged fragmental view showing the prongs as cut from the stock of the outer sleeve or wick-carrier and turned slightly inwardly to engage the fabric of the wick.

45 Figure 4 is the same as Figure 3, and showing the prongs as turned squarely inwardly.

Figure 5 shows the ends of the prongs as folded toward each other and clinched around a section of the fabric. Ordinarily the wick carrier tube is connected permanently to the wick by means of rivets, but it is found in practice that this is more or less expensive as it requires several operations, such as punching, inserting and sub-

sequently spreading the ends of the rivets, and to obviate this difficulty, I have provided a simple and effective means for attaching the tubular carrier to the wick, which is that of first inserting the wick into place into its carrier and then cutting or punching portions of the stock of the tube and turning these cut portions inwardly providing piercing prongs which pass through the fabric, and then fold the ends of these prongs to clinch them over the inner face of the fabric, all of which is done by the simple operation of cutting and punching with cutting and bending tools, thereby firmly attaching the tube to the wick; and the following is a detailed description of one means by which this result may be accomplished:—

With reference to the drawings, 10 designates the body portion of the oil-carrying fount into which the wick supporting collar 11 is threaded as at 12 and in this collar 11 is slidably mounted the tubular-wick carrier 13, which carrier is of a size to receive the wick 14 and just fit nicely around the same. The upper edge of this carrier is usually provided with a multiplicity of inturned prongs 15 which imbed themselves into the outer surface of the wick to assist in causing the wick to move with the carrier, but it is found in practice that these prongs are not sufficient in all cases to prevent the wick from slipping and that, therefore, it is necessary to more firmly secure the wick so that it cannot slip when the carrier is adjusted by the rotation of the adjusting gears 16 through its operating handle 17 connected to the outer end of the gear shaft 18. The teeth of this gear or pair of gears are arranged to enter any of the rows of vertically-disposed perforations or openings 19 in this sleeve. Therefore, in order to effect a permanent and binding connection between the carrier sleeve and the wick, I first insert the wick into the carrier and then place the same onto a suitably-shaped anvil 100 and pierce, cut or punch small sections of the stock of the sleeve as at 20, preferably having pointed ends arranged to form a pair of cooperating prongs 21, and I bend these cut portions or prongs inwardly, as illustrated in Figures 3 and 4, into staple form which, as they are turned to sweep inwardly from the surface of the sleeve, gather that portion of the threads of the fabric 22 which is within their sweep. These inwardly-ex-

- tending ends are then preferably folded towards each other, as illustrated in Figure 5, the inner surface 23 of these prongs being substantially flush with the inner surface 24 of the wick. The sleeve with its wick is then positioned over the inner or wick-tube 25 and these clinching members serve as bearings about the sleeve to support it against the working thrust of the operating gears 16, to prevent the sleeve from compressing the wick when subjected to a severe working strain of the gears upon the sleeve particularly when the sleeve is in its raised position.
- 15 By my improved method of securing the sleeve permanently to the wick, it is only necessary to first place the wick into the sleeve and then place the whole into the machine which first forms the prongs, then carries them inwardly through the wick fabric and subsequently clinches them on the inside thereof thus permanently securing the sleeve to the wick without necessitating the handling of small, separate parts such as rivets and the like, and without punching special holes for the reception of the rivets and without the operation of spreading the rivet ends after the rivet has been positioned.
- 20 By my improved method the stock of the sleeve itself is employed for forming the prongs.
- 25 My improved means for connecting the sleeve to the wick is extremely simple and practical and effective in its operation.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a wick-carrying sleeve integral prongs cut from the body of the wick-sleeve and folded inwardly to pierce and grasp a portion of the wick, said prongs having their end portions imbedded into the inner surface of the wick substantially flush therewith to bind the wick to the sleeve and also serve as a spacer to support the wick against compression when the sleeve is acted upon by the operating mechanism.
2. In a wick-carrying sleeve, substantially triangularly-shaped prongs cut from the body of the wick-sleeve and folded inwardly to pierce the wick, the pointed ends of said prongs being turned inwardly toward each other to embrace a portion of the wick, the end portions of said prongs being imbedded into the wick flush with the inner surface thereof to bind the wick against the body of the sleeve, said inturned prongs also serving as spacers to support the wick against compression and provide metallic slides for the sleeve when moved by the operating mechanism.

In testimony whereof I affix my signature.
JOHN CLITHEROE.
